UNITED STATES PATENT OFFICE.

NOAH Q. SPEER, OF PITTSBURG, PENNSYLVANIA.

SAND-DRIER.

SPECIFICATION forming part of Letters Patent No. 695,004, dated March 11, 1902.

Application filed April 11, 1901. Serial No. 55,300. (No model.)

To all whom it may concern:

Be it known that I, NOAH Q. SPEER, a citizen of the United States of America, residing at Pittsburgh, in the county of Allegheny and 5 State of Pennsylvania, have invented certain new and useful Improvements in Sand-Driers; and I do hereby declare the following to be a full, clear, and exact description thereof, reference being had to the accompanying drawings, 10 which form a part of this specification.

This invention relates to certain new and useful improvements in sand-driers, and has for its object to provide novel and effective means for drying the sand by the aid of steam 15 introduced into the receptacle which receives the sand, together with means for carrying off the condensation and for delivering the dried sand outside the drier.

Briefly described, the invention comprises 20 a receptacle to receive the sand. This receptacle has arranged therein a series of substantially horizontal pipes, the latter being only at sufficient inclination to carry off the water or condensed steam and provided at 25 their lower ends with cocks for carrying off this water or condensed steam. These pipes are connected to a common steam-supply and are supported within the receptacle by channel-beams, which form passage-ways for the 30 steam arising from the damp sand, these passage-ways leading to flues in the wall of the sand-receptacle, these flues connecting with a main flue, in which a fan is arranged for forming a forced draft to draw off this steam. 35 The dried sand is delivered through a chute to a traveling carrier or endless belt, which carries the sand outside the drier. All of this construction, together with other details entering into my invention, will be hereinafter 40 more specifically described and then particularly pointed out in the appended claim, and in describing the invention in detail reference is had to the accompanying drawings, forming a part of this specification, and wherein like 45 numerals of reference will be employed to designate like parts throughout the several views of the drawings, in which—

Figure 1 is a detail side elevation of my improved sand-drier. Fig. 2 is an end view of 50 the same. Fig. 3 is a view of the opposite end of the drier. Fig. 4 is a top plan view of my improved drier. Fig. 5 is a transverse

vertical sectional view taken on the line 55 of Fig. 1. Fig. 6 is a detail perspective view of one of the channel-bars by means of which 55 the steam-pipes are supported within the drier.

To put my invention into practice, I form a suitable support consisting of masonry-work 1 or the like, and upon this bed is supported 60 the sand-receptacle 2. This sand-receptacle is closed on the sides and at the ends, and the bottom comprises two downwardly-inclined walls converging toward a common line, these walls 3 forming a chute for delivering the 65 dried sand to the endless belt or carrier 4. This endless belt or carrier 4 is mounted on pulleys 5, carried on shafts 6, which are journaled in suitable bearings carried by the bed 1, one of said shafts having a pulley 7 for 70 connecting with the drive-belt. (Not shown.)

Extending lengthwise through the sand-receptacle 2 is a series of parallel rows of steam-pipes 8, these pipes being arranged above each other in rows, with the lowermost pipes 75 preferably of smaller diameter than the upper rows, as it is desired to feed a greater quantity of steam into the pipes that lie within the body of the sand. These pipes are connected at their one end to a common steam-supply 9, with their other ends extending through the opposite end wall of the receptacle and provided with removable caps 10 and also carry drip-cocks 12. These pipes are slightly inclined toward this latter end of 85 the receptacle, so that the condensed steam or water therein will be conducted to this end of the pipes and when the drip-cocks are opened will be discharged into troughs 14, each of which connect with a common discharge-pipe 15. These pipes are supported within the sand-receptacle by means of channel-bars 16, which are secured in the side walls of the receptacle and which register at their one end with vertical flues 17 in one of 95 the side walls of the receptacle. These vertical flues communicate at their upper ends with a horizontal flue at the top of the side wall, this flue 17 being connected to a fan 18, which is suitably supported from a bracket 100 19 at one end of the sand-receptacle.

The sand is placed within the receptacle at its top, and the steam being introduced into the pipes this sand is dried as it filters down

between the pipes forming the series of rows within the receptacle. These pipes being at a slight incline, any condensation of the steam that takes place within the same is easily 5 drained off at the lower end thereof. The steam arising from the damp sand is conducted by the flues in the channel-beams which support the pipes to the vertical flues in the side wall and up these flues to the 10 horizontal flue at the top of the receptacle by reason of the forced draft created by the fan at the discharge of the horizontal flue. The endless carrier or belt forms practically the 15 bottom of the receptacle, as it will be observed that the sand can be discharged only in an amount as is permitted by the space between the lower edge of the inclined walls and the carrier.

Having fully described my invention, what 20 I claim as new, and desire to secure by Letters Patent, is—

A sand-drier, comprising in combination with the walled inclosure, having vertical flues in one of its inner walls, channel-irons open on their under sides supported by the 25 opposite walls of said inclosure, said channel-irons opening on one side of the inclosure into said flues, and closed at their other ends, series of communicating steam-pipes resting upon said channel-irons, a hopper underneath the lower series of pipes and connecting the opposite walls of the inclosure, an endless carrier located adjacent to the outlet 30 end of said hopper, as set forth.

In testimony whereof I have hereunto affixed my signature in the presence of two subscribing witnesses.

NOAH Q. SPEER.
